UNITED STATES PATENT OFFICE

ALBERT E. GANZERT, OF CHICAGO, ILLINOIS, ASSIGNOR TO THE PYLE-NATIONAL COMPANY, OF CHICAGO, ILLINOIS, A CORPORATION OF NEW JERSEY

CONNECTER FOR ELECTRIC-TRAIN LIGHTS AND THE LIKE

Application filed August 5, 1927. Serial No. 210,771.

My invention relates to a connector socket adapted to be mounted on the end of a railroad car and to serve as a part of the system electrically connecting the cars in a train. It has for one object to provide a new and improved insulating socket and connector which will be more durable and reliable and wherein the possibility of damage to the connector socket by careless assembly is reduced to a minimum. Other objects will appear from time to time throughout the specification and claims.

My invention is illustrated more or less diagrammatically in the accompanying drawings, wherein—

Figure 1 is a front elevation of a connector and its supporting means;

Figure 2 is a side elevation of the same;

Figure 3 is a perspective of the insulating box;

Figure 4 is a section along the line 4—4 of Figures 3 and 7;

Figure 5 is a section along the line 5—5 of Figure 6;

Figure 6 is a section along the line 6—6 of Figures 3 and 7;

Figure 7 is a plain view of the device shown in Figure 3 with the cover removed;

Figure 8 is a plan view of the cover and bottom which are similar;

Figure 9 is a perspective of the insulating floating block.

Figure 10 is a section along the line 10—10 of Figure 2.

Like parts are indicated by like characters throughout the specification and drawings.

A is a metallic housing or box having ears A¹ and a cover A² held in place by the cap screws A³. This housing is intended to be bolted on the underside of the end or platform of a car. The ears A¹ are bored out for bolts. Lugs A⁴ carrying a pivot pin A⁵ on which the cover A⁶ is pivoted, there being a spring A⁷ to hold it in closed position is provided to close the front end of the box, this cover having a packing sheet A⁸ so that when it is held down by the spring and the housing closed, dust, water and the like cannot get in.

Contained within the housing A is an insulating conductor box made up of top and

bottom walls B B¹, side walls B² B² and back wall B³ of insulating material held together by means of screws B⁴ as indicated. Contained within this box or housing are a plurality of conductor sockets B⁵ B⁶. These conductor sockets are enclosed within the box being held by any suitable means. Each socket comprises a rigid upper limb B⁷, a thin spring B⁸ spaced below the upper limb and embedded in the bottom of the conducting material as at B⁹. This spring has a downwardly turned lip B¹⁰ which penetrates behind a shoulder B¹¹ in the bottom plate or wall B¹, the object being to protect the end of this spring so that when a plug is inserted, there is no possibility of the plug engaging the spring anywhere but at a point where it will guide the plug into the circuit.

C is a tapered conductor terminal apertured at C¹ so that the conductor may be wedged therein. The tapered portion terminates in a threaded shank C² on which is threaded a nut C³ and washer C⁴ so that when the nut is drawn up, the tapered terminal will be socketed in and held in closed electric contact with the body of the sockets B⁵ B⁶ thus making a satisfactory electric contact. C⁵ is an insulating filler block interposed between the sockets B⁵ B⁶ to insulate them and hold them apart in proper position in the housing and insulating box.

It will be noted that the underside of the top B and the upper side of the bottom B¹ are both recessed as at D D¹. D² is a loose insulating plate loosely held in these two recesses so that it furnishes an insulating partition between the two sockets. D³ is a clamping plate extending across beneath the sockets B⁵ B⁶ and adapted to be engaged by the clamp screw D⁴ threaded in a boss D⁵ in the cover A² manipulated by a hand wheel D⁶ whereby when a plug is pushed into a socket, the wheel may be operated to force the springs B⁸ snugly up against the plug and lock the plug in the socket.

When there is a plug in the socket, the cover A⁶ is of course held open and may rest against the surface of the conductor leading from the plug. When the plugs are withdrawn

the cover is forced down by the spring and closes the socket.

I claim:

1. In an insulating box for electric train circuit connecters and the like, a plurality of conductor sockets contained therein, the opposed walls of the box being recessed and an insulating plate loosely held against displacement within the recess interposed between the conductor sockets.
- 10 2. In an insulating box for electric train circuit connecters and the like, a plurality of conductor sockets contained therein, the opposed walls of the box being recessed and an insulating plate loosely held within the recess interposed between the conductor sockets, the conductor sockets having spring sides, means contained within the box for displacing the spring sides to grip a contact member in the socket, the insulating plate being cut away so as not to be engaged by such gripping member when it is tightened up.
- 15 3. A connecter for electric train circuits and the like comprising an insulating box, a conductor socket contained therein, registering apertures in opposed walls of the box, a tapered aperture in the socket concentric therewith, a tapered sleeve adapted to penetrate the box adapted to fit the aperture in the socket and to project on both sides beyond the box, the sleeve having a threaded end, a nut engaging such threaded end abutting against the outer wall of the box to draw the sleeve longitudinally through the box and seat it in the tapered aperture.
- 20
- 25
- 30
- 35

Signed at Chicago, county of Cook and State of Illinois, this 3rd day of August, 1927.

ALBERT E. GANZERT.
